SQUARE PLUG FLANGER

Edward V. Crane and Frederick G. Auer, Brooklyn, N. Y., assignors to E. W. Bliss Company, Brooklyn, N. Y., a corporation of Delaware

Application February 1, 1943, Serial No. 474,262

15 Claims. (Cl. 153—25)

The present invention relates to container making machinery and more particularly to a machine for flanging the ends of container bodies which are other than cylindrical in cross-section. The flanging operation is preparatory to securing the end in place and requires the deformation of the ends of the can body, generally by bending the same outwardly.

When a cylindrical body is subjected to a flanging operation, the fact that all points at which the body intersects a plane normal to the axis of the can and at which the flanging tool engages the body are equidistant from the axis enables a flanging operation to be performed without the use of holding dies and without undesirable bending of the body out of round. On the other hand, when any other can body, as for instance a square can, is to be flanged, parts of the surface to be deformed are closer to the axis than the other parts. Unless gripping jaws are provided to hold the can in shape it will tend to assume a cylindrical cross-section where the flanging die is forced into the body. This is due to the stretch imparted to the metal during flanging.

Flanging machines have been built which are provided with gripping jaws to hold the can and retain it in shape while the flanging dies enter the can body and bend the can edges outwardly to the desired position. It has also been common practice to provide feeding motion for advancing the can body in timed relation to the flanging and edging operations.

The various motions employed were of necessity timed in order to provide the proper sequence of operations. This was done by the use of cam mechanisms, using the dwells on the cams to insure the desired timing action. Such constructions were expensive to build and the operation of the cams in the region of the dwells required more power than was desirable.

The general object of the present invention has been to provide an improved driving mechanism to impart such motions to the parts. A further object has been to incorporate in such driving mechanism a plurality of linkage means including a series of toggle levers to provide dwells where two or more links move through a region of alignment. This means that period when between two links which are in alignment with each other and are moving through arcs about their pivot points the least motion of one link toward or away from the other is taking place. By the judicious use of these dwells the speed and sequence of the various motions can

be controlled. Likewise, the time interval for various movements, or the time when there is no movement, can be controlled.

One of the advantages of a machine constructed as herein disclosed is that the use of toggle mechanisms of predetermined coordinated dwells permits of the operation of the machine at higher production rates than heretofore attained and without the resulting shock and wear characteristic of prior structures wherein cams and cranks were used. When attempts were made to increase the speed of such prior art machines the violence of reversal of cam action, etc., at such higher speeds resulted in rapid depreciation as well as disruption in the precision of coordination acquired. Furthermore, it has been found that a machine as herein disclosed can be manufactured at considerably less cost than the manufacturing cost of machines heretofore made for like purposes.

To the accomplishment of the foregoing and related ends, said invention, then, consists of the means hereinafter fully described and particularly pointed out in the claims; the annexed drawings and the following description setting forth in detail certain mechanism embodying the invention, such disclosed means constituting, however, but one of various means in which the principle of the invention may be used.

30 In said annexed drawings—

Fig. 1 is a side elevation of the assembled machine;

Fig. 2 is an elevation along lines 2—2 of Fig. 1 with some parts shown in section and some parts broken away;

Fig. 3 is in part an elevation and in part a sectional view showing the drive connections;

Fig. 4 shows the upper part of the machine in a side view similar to Fig. 1 on an enlarged scale, with some parts broken away;

Fig. 5 in a similar way shows the upper part of Fig. 2 on an enlarged scale;

Fig. 6 is a more detailed view of the delivery chute and of the mechanism associated therewith;

Fig. 7 is a top plan view of the parts shown in Fig. 6;

Figs. 8 to 14 are diagrammatic illustrations of the operating mechanisms, Figs. 8 and 9 showing the gripping mechanism in open and closed positions respectively, Figs. 10 and 11 the flanging mechanisms open and closed, and Figs. 12, 13 and 14 different positions of the feeding mechanism.

55 Referring more particularly to Fig. 1, the ma-

chine is shown to include a feed chute generally designated by 15, from which the cans 16 are fed to a reciprocating cradle mechanism 17 which carries them in the direction of the arrow to a flanging station C.

The flanging station is located in the upper part of the machine within the confines of a frame 20 sitting upon the top of the main machine frame structure. The latter comprises a base 21 and two upright portions 22 and 23 in front and rear.

As shown at the right side of Fig. 1 a casing 25 encloses the drive mechanism, comprising a motor M, a flywheel 27, a gear and pinion mechanism 29, 30 and a clutch 31, all of which will be more fully described below with reference to Fig. 3.

The lower part of the machine frame houses the crankshaft 33. The crankshaft has a crank pin covered by a cap 34 which extends into the brake housing 35, which is secured to plate 23.

Mounted within the machine frame are, furthermore, a number of linkage systems, the central system being a system of toggle levers designated in a general way by 37, said system operating the gripping jaws. A second system of levers, designated by 38, operates the flanging members, two rods, 39 and 139 respectively, transmitting the movement from the bottom part to the top part of the machine (Fig. 2). Finally a system of links serves to actuate the feeding mechanism. The latter system is operated from the crankshaft through a pinion 41 in engagement with a rack 42 and comprises links 43 to 46.

In Fig. 3 the motor is again shown at the right-hand side of the machine mounted in a housing 50 on a pedestal 51. The shaft 52 of motor M carries a pulley 26 which is connected by the usual belting to flywheel 27. The latter is rigidly fastened by means of a bolt 53 to the end of a shaft 28 which is journaled in bearing collars 54 and 56 on parts 55 and 57 of the machine frame. Mounted for rotation with said shaft 28 is a pinion 29 in mesh with gear 30. The hub of gear 30 is carried in bearing rings 59 and 60 on a cylinder 61 which forms part of a so-called "rolling key clutch," well known in the art. Key 62 engages to connect the crankshaft part 64 to the drive gear 30. The engagement and disengagement of the clutch and the crankshaft is brought about by a system of levers 65, 66 and 67 actuated from a shaft 69 by means of a hand-operated bar 70.

The same bar serves for operating the brake when the bar is moved to a different position. The brake which is applied when it is desired to stop the crank after disengagement of the clutch, is enclosed in a housing 35. The construction of the brake is well known and has, therefore, not been shown in the drawings. It is a toggle brake with a pair of friction pads on shoes encircling the outside of little brake wheels and releasing the wheels when the toggle is straightened, while being pulled toward said wheels and applying the brake when the toggle is broken.

The crank pin 36 on crankshaft 33 furnishes the drive for all the parts of the machine, that is to say, all the system of toggle levers and other drive transmission means mentioned above with reference to Fig. 1 are coupled to the crank pin 36.

As shown in Fig. 6 the chute 15 comprises inclined rails 72 along which a series of cans 16 is fed from the can body maker to the feed mechanism of the flanger. Adjoining the inclined rail 72 is an inclined portion 73 of the delivery chute for directing a can 16 to the above mentioned cradle mechanism 17 mounted on channel-shaped

feed bars 82. The cradle mechanism is mounted in these bars so as to be reciprocated therewith by the action of the arm 45 and rod 46 which form part of the feed mechanism later to be described.

5 The portion 73 has top surfaces formed at a smaller angle with respect to the horizontal plane than rails 72, whereby a smoother reception of the cans as they leave the chute will be made possible. Pivotedly mounted stops 75 and 76 are provided in the path of the cans which block the travel of a can before the cradle can take it to the flanging station and release a can as soon as the preceding one is removed. Stop 75 is mounted on a bell crank lever 71, which is pivoted at 80 to a chute member and at 80' to a lever 78 linked to the slide members carrying the top clamps, as indicated by reference numeral 79. A spring 81 buffers the thrusts of lever 78 should stop 75 foul on a can body, the action of said lever being timed with the flanging members.

The cradle mechanism 17 comprises a series of troughs 74^a, 74^b and 74^c, which successively receive a can 16, carry it from station to station in the flanging mechanism and feed it out from there after the flanging operation is finished. The flanging mechanism is more fully shown in Figs. 4 and 5. Referring more particularly to Fig. 4, a can is shown on arrival from the delivery chute as it is received between two clamping jaws 90 and 91. The can is held between these jaws until the trough 74^a, which in the drawings is shown in midtravel, reaches the extreme left position in vertical alignment with jaw 91. At this time the jaws open to release the can, which is picked up through 74^b and carried forward therein until it reaches a position underneath station A, in which it undergoes its first flanging operation. The lifting mechanism required for moving a can up to the position A is described below.

40 After a can has been worked upon in station A it is lowered again to the cradle, received in trough 74^b, and therein moved on to a position underneath station B. As actually shown in the drawings, cradle 74^b is on its way from A to B. 45 After the can has been flanged in station B it is dropped again, received in trough 74^c and carried out of the flanging station.

Two pairs of clamping jaws 90, 91 are provided for embracing the entire periphery of a can at each end, to lift the can from the troughs to the clamping stations and to hold it there during the flanging operation. The arrangement which affords relative movement between the upper and lower clamping jaws is best seen from Fig. 5. In 50 this figure vertical rods 93 are shown which guide a pair of slideways 95 comprising integral parts of a cross-frame 99. The rods 93, in turn, are supported by the machine frame, as shown in Fig. 5. Carried by said cross-frame are angles 97 to which the lower jaws 91 are rigidly secured by bolts. The upper jaws 90 are bolted to angles 96 which are in turn securely fastened to a cross-frame 98 carrying members 94. The latter are fastened to rods 93 by nuts 83. Thus, as slideways 95 are reciprocated on rods 93 the lower clamping jaws 91 are moved into and out of engagement with jaws 90 for gripping, lifting, holding and releasing a can respectively.

In Fig. 5 the channel bars 82 are shown to be 70 adjacent to the lower jaws 91 and movable in a transverse direction thereto. The channel bars are connected by a spacing rod 100, to which rod 46 is linked at 101, while the pivot connection 102 leads to arm 45 (Fig. 4).

A can 16 is shown in position for being flanged

by the heads 103 of flanging members arranged for flanging action at both can ends. Details of the flanges have not been shown because they are of known construction.

The drive mechanism for the gripping jaws and the flanging members will now be described with reference to Fig. 2. From crank 33 a connecting rod 110 leads to a substantially triangular lever 112, hereinafter called the central lever. The lever is pivotally mounted on the machine frame at 112^a and linked to connecting rod 110 on a pivot 111. As the crankshaft rotates, connecting rod 110 moves pivot 111 back and forth along a more or less horizontal line, thereby also rocking the central lever. Fastened to said lever at 113 is a link 114 which is pivoted at 115 to a T-shaped lever 116, the latter being pivotally mounted at 126 to the machine frame. One end of lever 116 has a pivot 117 to which is also linked a portion 118 of an adjustable rod connection, the other part of which is designated by 120. A threaded member 119 connects portions 118 and 120 making them capable of adjustment. Member 120 is linked at 121 to the lower frame 122 which is part of frame 99 carrying the lower jaws 91. Fastened to the other end 123 of lever 116 is a similar adjustable rod connection comprising parts 128, 129 and 130, the latter being pivoted at 133 to a cross-member 131. This member in turn connects brackets 132 to the two rods 93 which slide in slideways 95 mentioned above. As shown in Fig. 5, the rods 93 are slidably supported in the upper reaches thereof by brackets and by lugs 93^a integrally formed on the machine frame members 22 and 23 to support said rods.

Figs. 8 and 9 are working diagrams which show the operation of the gripping jaws. Fig. 8 shows the open position of jaws 90 and 91 to which the broken position of the toggle lever system 112, 116, 118 to 120 and 128 to 130 corresponds. As the connecting rod pulls 111 to the right, link 114 moves up from the position shown in Fig. 8 to that shown in Fig. 9, pivot 117 of lever 116 is raised and pivot 123 lowered, moving the rod members 118 to 120 and 128 to 130 to straight up and down positions respectively, and at the same time driving the gripping jaws into operating or closed position. The position of the gripping jaws is the one also shown in Fig. 2.

It will be noted that when the gripping jaws are in closed position there is what we call a three-point dwell. A dwell is obtained between two pivoted links when they are so moved with respect to each other that their two pivoted points and their common point are substantially in alignment. That means that at this time here is the least tendency of the two links to be pushed apart because their arcs of rocking or swinging are most nearly tangent. The three points of dwell are at a, b and c in Fig. 9.

Reverting once more to Fig. 2, the mechanism for operating the flanging members will now be described. For that purpose two pairs of toggle lever systems are provided, one located in the lower portion of the machine and one on top near the flanging dies proper; the lower and the upper systems on each side of the machine are connected to each other by rods 39 and 139 respectively.

At the left-hand side of the machine is a rock shaft 140 having arms 142 and 142^a. Arm 142 is connected to triangular lever 112 by link 143. Pin 138 and 142^a connects rod 39, which, as mentioned above, leads up to the second toggle lever system. This system comprises a bell crank 153

pivoted to the machine frame at 155 and linked to rod 39 at 152. The other arm of the bell crank is pivoted at 154 to a link 156 which in turn is pivoted at 157 to the slidable flanging dies 158.

An extension of arm 142 is pivotally connected to a rod 146, which extends to the right of the machine in slightly downward direction. At its other end rod 146 is linked to one arm of a bell crank 150 pivoted idly on the crankshaft 33. The other arm of the bell crank is pivotally mounted on rod 139 which extends to a toggle lever system that is the duplicate of the one described for the left-hand side of the machine.

The operation of the flanging dies will now be described with reference to Figs. 10 and 11. In Fig. 10 the dies are in open position. As lever 112 moves to the right it pulls link 143 up, thereby moving the composite arm 142 into the position shown in Fig. 11. The movement of arm 142 pulls rod 146 to the left, thereby moving bell crank 150 to pull down rod 139. Rods 39 and 139 are moved down simultaneously by the center arm 142 which, during the rocking movement, changes from the up position shown in Fig. 10 to the down position shown in Fig. 11. As both rods 39 and 139 move down they pull cranks 153 down, thereby pushing the dies 158 toward each other.

While the arrangement and operation have been described for one pair of flanging members cooperating in the first flanging action in station A (Fig. 4), it will be understood by those skilled in the art that a duplicate pair of flangers, which serve to complete the two-stage flanging operation in station B, may be actuated in a similar way by sliding die members corresponding to members 158.

In this case there will be a two-point dwell when the dies are in closed position. The respective points are marked c and d in Fig. 11.

The drive for the cradle rocking or can feed mechanism is shown in Figs. 1, 2 and 12 to 14. The connecting rod 110 carries an arm 160 to which a rod 40 is connected for vertically reciprocating movement. This rod has its other end linked to a member 161 carrying the rack 42 (Fig. 1). Rack 42 is in mesh with a pinion 41, to which an arm 32, pivotally connected to a link 43 is attached. Pinion 41 is journaled in a bearing 162 and attached to the machine frame, (Fig. 12).

Line 43 is pivotally connected to arm 44 of a rock shaft 47, provided with a second arm 45. Connecting rod 46 connects arm 45 of the rock shaft with the slide bars 82 for longitudinal reciprocation of the cam cradle 17.

As best seen in Figs. 12 to 14 the reciprocating movement of connecting rod 110 moves rod 40 and thereby rack 42 up and down. This causes pinion 41 to turn alternately to the left and to the right, thus oscillating arm 32. As this oscillation takes place link 43 is moved back and forth and the movement is transmitted over arms 44, 45 to rod 46, which finally causes the reciprocation of the cradle slide 82. Fig. 13 shows the pinion in midstroke of the feeding mechanism, Fig. 14 shows the up end position in which a dwell occurs. Another dwell is reached in the down end position. In one of these positions the cradle is beneath one of the flanging stations; in the other it is in the position to receive a can from the delivery chute.

Other modes of applying the principle of our invention may be employed instead of the one explained, change being made as regards the mech-

anism herein disclosed, provided the means stated by any of the following claims or the equivalent of such stated means be employed.

We therefore particularly point out and distinctly claim as our invention:

1. In a flanging machine comprising a frame, a cradle mechanism for feeding cans to the flanging station proper, gripping jaws in said flanging station for clamping said cans for the flanging action and flanging members for bending back the can edges to an angle with the can body, in combination a central lever pivotally mounted to said frame, means for reciprocating said lever, a T-shaped toggle lever linked at one of its pivot points to said central lever a link member, said T-shaped toggle lever being connected at its other pivot point to said link member, both said T-shaped toggle lever and said link being capable of connecting said central lever and said gripping jaws for moving the latter into and out of clamping engagement with a can to be flanged.

2. In a flanging machine comprising a frame, a cradle mechanism for feeding cans to the flanging station proper, gripping jaws in said flanging station for clamping said cans for the flanging action and flanging members for bending back the can edges to an angle with the can body, in combination, a system of toggle levers for operating said gripping paws, said system comprising a central lever having a plurality of connecting points, said central lever being pivotally mounted to said frame, a crankshaft for reciprocating said central lever, a connecting rod for connecting said crankshaft and said central lever and being pivoted to one of said pivot points of said central lever, T-shaped toggle lever being linked to another of said pivot points of said lever, a connecting member, said T-shaped lever being linked at a second pivot point to said connecting member, said member being capable of connecting said gripping jaws to said central lever for moving said jaws into and out of engagement with a can to be flanged, said toggle lever system having a three-point dwell.

3. In a flanging machine comprising a frame, a cradle mechanism for feeding cans to the flanging station proper, gripping jaws in said flanging station for clamping said cans for the flanging action and flanging members for bending back the can edges to an angle with the can body, in combination a system of toggle levers for operating said flanging members, said system comprising a central lever having a plurality of connecting points, said lever being pivotally mounted to said frame, means for reciprocating said lever comprising a connecting rod having one end pivoted to said lever, a pair of toggle means, one of said pair being linked to one connecting point of said lever and the other one of said pair being linked to one end of a second connecting rod, whose other end is linked to said first mentioned toggle means, means for moving said flanging members into and out of operating position, and two elongated members, one at each side of the machine, for connecting said toggle means to said means for moving said flanging members.

4. In a flanging machine comprising a frame, a cradle mechanism for feeding cans to the flanging station proper, gripping jaws in said flanging station for clamping said cans for the flanging action and flanging members for bending back the can edges to an angle with the can body, in combination a system of toggle levers for operating said flanging members, said system comprising a central lever having a plurality of con-

necting points, said lever being pivotally mounted to said frame, means for reciprocating said lever comprising a connecting rod having one end pivoted to said lever, a pair of toggle means, one of said pair being linked to one connecting point of said lever and one of said pair being linked to the other end of a second connecting rod, whose other end is linked to the first mentioned toggle means, a second pair of toggle means for moving said flanging members into and out of operating position, and two elongated members, one at each side of the machine, for connecting said first mentioned pair of toggle means to said second mentioned pair of toggle means.

5. In a flanging machine comprising a frame, a cradle mechanism for feeding cans to the flanging station proper, gripping jaws in said flanging station for clamping said cans for the flanging action and flanging members for bending back the can edges to an angle with the can body, in combination a system of toggle levers for operating said flanging members, said system comprising a central irregularly shaped lever being pivotally mounted to said frame and having three connecting points, means for reciprocating said lever comprising a connecting rod having one end pivoted to said lever at one connecting point of said lever, a pair of toggle means, one of said pair being linked to another connecting point of said lever and the other one of said pair being linked to the other end of a second connecting rod, whose other end is linked to the first mentioned toggle means, a second pair of toggle means for moving said flanging members into and out of operating position, and two elongated members, one at each side of the machine, for connecting said first mentioned pair of toggle means to said second mentioned pair of toggle means.

6. In a flanging machine comprising a frame, a cradle mechanism for feeding cans to the flanging station proper, gripping jaws in said flanging station for clamping said cans for the flanging action and flanging members for bending back the can edges to an angle with the can body, in combination a system of toggle levers for operating said gripping jaws and said flanging members in timed relationship, said system comprising a central lever being pivotally mounted to said frame and having a plurality of connecting points, means for reciprocating said central lever comprising a connecting rod having one end pivoted to said lever at one connecting point of said lever, one toggle means being linked to another connecting point on said central lever and adapted to move said gripping jaws into and out of engagement with a can to be flanged, a pair of toggle means, one of said pair being linked to a third connecting point of said central lever and the other one of said pair being linked to one end of a second connecting rod, whose other end is linked to said first mentioned toggle means of said pair means for moving said flanging members into and out of operating position, and two elongated members, one at each side of the machine, for connecting said pair of toggle means to said means for moving said flanging members.

7. In a flanging machine comprising a frame, a cradle mechanism for feeding cans to the flanging station proper, gripping jaws in said flanging station for clamping said cans for the flanging action and flanging members for bending back the can edges to an angle with the can body, in combination a system of toggle levers for operating said gripping jaws and said flanging members in timed relationship, said system compris-

ing a central lever being pivotally mounted to said frame and having a plurality of connecting points, means for reciprocating said central lever comprising a connecting rod having one end pivoted to said lever at one connecting point of said lever, one toggle means being linked to another connecting point on said central lever and adapted to move said gripping jaws into and out of engagement with a can to be flanged, a pair of toggle means, one of said pair being linked to a third connecting point of said central lever and the other one of said pair being linked to one end of a second connecting rod, whose other end is linked to said first mentioned toggle means of said pair means for moving said flanging members into and out of operating position, and two elongated members, one at each side of the machine, for connecting said pair of toggle means to said means for moving said flanging members and a plurality of links for operating said feeding mechanism.

8. In a flanging mechanism comprising a cradle mechanism for feeding cans to the flanging station proper, gripping jaws in said flanging station for clamping said cans for the flanging action and flanging members for bending back the can edges to an angle with the can body, in combination a system for operating said feeding mechanism, said system comprising a crankshaft, a connecting rod operated by said crankshaft, a rack linked to said connecting rod so as to be moved up and down thereby, a pinion mounted for engagement with said rack as the same is moved up and down by said connecting rod and linkage means operated by said pinion for reciprocating said feeding mechanism.

9. In a flanging mechanism comprising a cradle mechanism for feeding cans to the flanging station proper, gripping jaws in said flanging station for clamping said cans for the flanging action and flanging members for bending back the can edges to an angle with the can body, in combination a system for operating said feeding mechanism, said system comprising a crankshaft, a connecting rod operated by said crankshaft, a rack linked to said connecting rod so as to be moved up and down thereby, a pinion mounted for engagement with said rack to be turned back and forth on said rack as the rack is moved up and down and a plurality of links operated by said pinion for reciprocating said feeding mechanism.

10. In a flanging machine comprising a frame, a cradle mechanism for feeding cans to the flanging station proper, gripping jaws in said flanging station for clamping said cans for the flanging action and flanging members for bending back the can edges to an angle with the can body, in combination a system of linkage means for operating said feeding mechanism, said gripping jaws and said flanging members in timed relationship, said system comprising a central lever being pivotally mounted to said frame and having a plurality of connecting points, means for reciprocating said central lever comprising a connecting rod having one end pivoted to said lever at one connecting point of said lever, toggle means linked to another connecting point on said central lever and adapted to move said gripping jaws into and out of engagement with a can to be flanged, a pair of toggle means, one of said pair being linked to a third connecting point of said central lever and the other one of said pair being linked to one end

of a connecting rod, whose other end is linked to said first mentioned toggle means of said pair, means for moving said flanging members into and out of operating position, and two elongated members, one at each side of the machine, for connecting said pair of toggle means to said means for moving said flanging members and a plurality of links for operating said feeding mechanism.

10. 11. In a flanging mechanism comprising a frame, cradle mechanism for feeding cans to the flanging station proper, gripping jaws in said flanging station for clamping said cans for the flanging action and flanging members for bending back the can edges to an angle with the can body, in combination a system of linkage means for operating said feeding mechanism, gripping jaws and flanging members comprising a central lever of irregular shape pivotally mounted in said frame, said lever having a plurality of connecting points for actuation of said gripping and flanging mechanisms from a single center, means for reciprocating said lever, and toggle means for connecting said lever and said gripping jaws, said means being capable of moving said jaws into and out of clamping engagement with a can to be flanged.

12. In a flanging machine comprising a frame, a cradle mechanism for feeding cans to the flanging station proper, gripping jaws in said flanging station for clamping said cans for the flanging action and flanging members for bending back the can edges to an angle with the can body, in combination a system of toggle levers for operating said flanging members, said system comprising a central lever having a plurality of connecting points, said lever being pivotally mounted to said frame, means for reciprocating said lever comprising a connecting rod having one end pivoted to said lever, a pair of toggle means, one of said pair being linked to one connecting point of said lever and the other one of said pair being linked to one end of a second connecting rod, whose other end is linked to said first mentioned toggle means, means for moving said flanging members into and out of operating position, two elongated members, one at each side of the machine, for connecting said toggle means to said means for moving said flanging members, and a cross-member mounted on opposed gripping jaws so as to extend between them through the width of the flanging station thereby increasing the resistance of the structure against the action of said flanging members.

13. In a flanging machine comprising a frame, a cradle mechanism for feeding a plurality of cans to flanging stations proper, pairs of gripping jaws in said flanging stations for clamping said cans during the flanging action and pairs of flanging members for bending back the can edges to an angle with the can body, in combination a system of toggle levers for operating said flanging members, said system comprising a central lever having a plurality of connecting points, said lever being pivotally mounted to said frame, means for reciprocating said lever comprising a connecting rod having one end pivoted to said lever, a pair of interconnected toggle means, one of said pair being linked to one connecting point of said lever, means for moving said flanging members into and out of operating position, and two elongated members, one at each side of the machine, for connecting said toggle means to said means for moving said flanging members.

14. In a flanging mechanism comprising a re-

ciprocating cradle mechanism for feeding cans to the flanging station proper, gripping jaws in said flanging station for clamping said cans for the flanging action and flanging members for bending back the can edges on the can body, means for operating said cradle mechanism, gripping jaws and flanging members to provide timed dwells in the respective movements thereof, comprising a single main drive member and linkage means operated by the drive member and interconnecting the drive member with the cradle mechanism, gripping jaws and flanging members, said linkage means including toggle arrangements for providing timed dwells in the movements of said cradle mechanism, gripping jaws and flanging members.

15. In a flanging mechanism including a dual flanging station proper comprising two operating stations, cradle mechanism for feeding cans suc-

cessively to said operating stations, gripping jaws in said operating stations for clamping said cans for the flanging action and flanging members in each of said operating stations for bending back the can edges in a two-stage operation to an angle with the can body, means for actuating said cradle mechanism, gripping jaws and flanging members comprising, a single main drive member, and a system of linkage means operated by said main drive and interconnecting the drive member with said cradle mechanism, said gripping jaws and said flanging members, said linkage means including toggles for providing timed dwells in the respective movements of said cradle mechanism, gripping jaws and flanging members.
